UNITED STATES PATENT OFFICE.

MORGAN L. SWEENEY, OF LOS ANGELES, CALIFORNIA, ASSIGNOR TO UNION TANK & PIPE COMPANY, A CORPORATION OF CALIFORNIA.

METHOD OF SECURING JOINTS IN STOVEPIPE CASINGS.

Application filed September 21, 1922. Serial No. 589,496.

To all whom it may concern:

Be it known that I, MORGAN L. SWEENEY, a citizen of the United States, residing at Los Angeles, in the county of Los Angeles and State of California, have invented a new and useful Method of Securing Joints in Stovepipe Casings, of which the following is a specification.

My invention relates to the oil producing industry, and consists of an improved method of joining overlapping metal plates having a particular utility in the connection together of lengths of stove pipe casing as they are lowered into a well.

In California it is customary when drilling an oil well to start the hole with a large diameter and to reduce the diameter of the hole as the depth increases. In many instances the hole is started with a fifteen inch diameter, which may be continued for several hundred feet before reduction to a smaller size. It is customary to line the starting hole with stove pipe casing for the purpose of supporting the walls of the hole against caving. This is necessary because of the soft and crumbling nature of the subsurface formations.

The stove pipe casing ordinarily employed is made up in lengths comprised of sections of sheet metal, rolled into pipe form having their overlapping edges riveted together. These lengths of casing are made up of two layers of metal with the respective joints thereof overlapping, so that where two consecutive inner members abut, the outer member serves as a support for the joint and where a joint occurs between two outer members an inner member serves as a support. Being thus made up of inner and outer lengths, the sections of casing are provided with a projecting inner pipe at one end and a projecting outer pipe at the opposite end. In placing the casing in a well, the projecting ends of the inner layer in the lower end of one section are inserted in the projecting ends of the outer layer of the upper end of a lower section and the overlapping plates forming these projecting ends are riveted or otherwise secured together.

My invention provides a means for securely and expediently joining together the consecutive lengths of stove pipe casing as they are installed in a well, in making up the joints between casing lengths. In the

securing of these joints, my method employs 55 a standard oxy-acetylene welding equipment.

The especial advantages of the method and further objects thereof will be made evident 60 hereinafter.

Referring to the drawing which is for 65 illustrative purposes only:

Fig. 1 is a partially sectioned view showing the co-operating ends of two lengths of 70 stove pipe casing which are about to be joined together.

Fig. 2 is a partially sectioned view illustrating a joint which has been secured by the employment of my method.

Fig. 3 is a section taken on a plane represented by the line 3—3 of Fig. 2.

Fig. 4 is an enlarged fragmentary section illustrating the proportionate size and the disposal of the holes which are formed in the overlapping plates forming the casing 75 joint, preliminary to the fusing in of a metal securing key.

Fig. 5 is a fragmentary sectional view similar to Fig. 4, but showing a key welded 80 into the cooperating holes formed in the overlapping plates.

As shown in Fig. 1 of the drawing, stove pipe casing of the type previously described is made up of inner sections 11 and outer sections 12. The inner and outer sections 85 11 and 12 are so placed one upon the other in consecutive arrangement that the ends of the outer members 12 come together at a point 14 intermediate between the ends of the inner sections 11. It, therefore, follows 90 that the ends of the inner section come together at points intermediate between the ends of the outer sections. At one end of a length of casing half the length of an inner section 11 projects out from the end outer 95 sections 17 as indicated at 16, while upon the opposite end of the length of casing, as illustrated at 20, half of the outer section 21 projects beyond the end inner section 22.

Ordinarily in installing stove pipe casing 100 the projection 16 is inserted in the projection 21 as indicated in Fig. 2 and the overlapping portions 16 and 21 riveted together or secured by picking, thus joining the two lengths of casing together in the form of a 105 continuous length. The riveting of these lengths of stove pipe casing together has presented considerable difficulty owing to the

fact that the rivets must be bucked up from the inside, and in order to accomplish the bucking up, it is necessary to work from the end of the casing, which is at a considerable distance from the point at which the riveting is being done. The employment of picking alone has not been found entirely satisfactory, as sufficient strength is not provided thereby to prevent pulling apart of joints under severe pulling strain.

In my process holes 25 are formed in the outer extending portions 21 of the casing, and holes 26 of a slightly smaller diameter than the holes 25 are formed in the inner 15 projecting portions 16 in positions at which they will coincide with the outer holes 25 when the lengths of casing are put together as shown in Fig. 2. Each pair of the co-operating holes 25 and 26 are welded up 20 with a welding torch so that a key 30 is formed therein.

As shown in Fig. 4, the holes 26 in the inner plate 31, from which the inner projecting portion 16 is formed, is somewhat 25 smaller than the hole 25 in the outer plate 32 forming the outer member 21. An annular area 34 of the outer surface of the plate 31 is exposed around the opening 26 by the larger holes 25. When the lengths 30 of casing are placed together, the holes 25 and 26 coincide in the manner shown in Fig. 4. By employing a suitable welding torch a body or key 30 of metal is fused into the holes 25 and 26, the walls 36 of 35 the hole 26, the annular surface 34 exposed by the opening 25 and the wall 37 of the hole 25 being fused with the metal forming the key 30, so that an autogenous binding together of the two plates is accomplished. 40 The key 30 has the same function as a rivet but is much easier and quicker of installation, and has equal if not greater strength than a rivet; the strength of the joint provided by the key 30 being derived 45 from the broad surface of fusion between the key 30 and the plates 31 and 32, this surface of fusion being made up of the wall 36 of the opening 26 and the annular surface 34 of the plate 31, and the wall 37 50 of the hole 25 and the overlapping or flaring tendency of the key as indicated at 39, this flare being due to the tendency for sharp corners to fuse down under the action of a welding flame.

55 In some cases it may be necessary to employ a larger number of keys than punched holes 25 and 26 provided for. In this instance co-operating holes are burned through the overlapping plates 16 and 21 60 with a cutting torch, these co-operating holes then being welded up in the same manner as hereinbefore described. It is not

necessary to the successful practice of this method that the holes be previously formed.

Although I have described and illustrated my invention in connection with the securing of joints for stove pipe casing, it will be appreciated that the method will also be of utility in all cases where it is desired to secure one or more overlapping plates together which are subjected to translational stresses.

I claim as my invention:

1. The method of securing joints in stove-pipe casing, comprising; forming holes in one of the overlapping plates comprising said joints; forming cooperating holes of smaller diameter than said holes in said outer plates, in the other of said plates comprising said joints; and welding keys into 75 said outer holes and said cooperating inner holes.

2. The method of securing joints in stove-pipe casing, comprising; forming holes in one of the overlapping plates comprising 85 said joints; forming cooperating holes of smaller diameter than said holes in said outer plates, in the other of said plates comprising said joints; and welding keys into 90 said outer holes and said cooperating inner holes, said key being fused to the interior walls and the edges of said cooperating holes.

3. The method of securing joints in stovepipe casing, comprising; forming holes 95 in one of the overlapping plates comprising said joints; forming cooperating holes of smaller diameter than said holes in said outer plates, in the other of said plates comprising said joints; and fusing a body of 100 metal into each of said holes in said outer plates and its cooperating hole in said inner plates, said body being fused to the walls of said holes and filling said holes to form 105 a key between said overlapping plates.

4. The method of securing together a pair of overlapping plates, comprising; forming holes in the outer of said plates; forming cooperating holes in the inner of said plates, said inner holes being of smaller diameter 110 than said outer holes so that annular areas of the surface of said inner plate, around said inner holes, is exposed through said outer holes; and fusing a body of metal into each of said outer holes and its cooperating inner hole, said body being fused to the walls of said holes and said exposed surface of said inner plate, and overlapping the outer edges of the walls of said outer holes.

In testimony whereof, I have hereunto set my hand at Los Angeles, California, this 15 day of September, 1922.

MORGAN L. SWEENEY.
